DESIGN FOR A NAUTICAL GAME BOARD

Ernest B. Coxhead, Berkeley, Calif.

Application December 14, 1935, Serial No. 60,088

Term of patent 14 years

To all whom it may concern:

Be it known that I, Ernest B. Coxhead, a citizen of the United States and a resident of Berkeley, county of Alameda, State of California, have invented a new, original, and ornamental Design for a Nautical Game Board, of which the following is a specification, reference being had to the accompanying drawing, forming part thereof.

In the drawing, Fig. 1 is a plan view of a nautical game board showing the design of my invention.

Fig. 2 is a side elevation of the nautical game board shown in Fig. 1.

I claim:

The ornamental design for a nautical game board, as shown.

ERNEST B. COXHEAD.
